UNITED STATES PATENT OFFICE

GEORGE W. CUMING, OF NEW YORK, N. Y., ASSIGNOR TO M. A. CUMING & CO. INC., A CORPORATION OF NEW YORK

MACHINE FOR TREATING HAT BODIES

Application filed April 18, 1930. Serial No. 445,242.

My invention relates to machines for stretching and treating the crowns and the brims of unfinished hats, usually made of felt or the like.

5 More particularly stated my invention contemplates an improved machine in which a hat body is placed and operated upon, for the purpose of flattening out and stretching the brim, and forming the crown.

10 My invention contemplates a machine of the general type just mentioned, in which the crown and brim of the hat body are subjected to the action of steam, the brim being stretched radially outward.

15 My invention further contemplates the use of a hollow metal hat block to be detachably fitted into the crown of the unfinished hat, the hat block being provided with perforations through which steam passes into 65 the hat crown, and through the wall thereof.

In addition, my invention contemplates the use of a plurality of spacing disks of different thicknesses in connection with the hat block, for the purpose of varying the effective depth of the hat block.

20 My invention also comprehends various improvements in hat forming machines generally, for the purpose of improving the efficiency thereof.

25 Reference is made to the accompanying drawings forming a part of this specification, and in which like reference characters indicate like parts throughout all of the figures.

30 Figure 1 is a side elevation of my device, here shown as partly broken away.

Figure 2 is a substantially central vertical cross section through the mechanism shown in Figure 1.

35 Figure 3 is a fragmentary plan of the steam chamber and mechanism carried thereby, certain parts being removed and others being shown as broken away.

40 Figure 4 is a side view, partly an elevation and partly a central section, showing the improved hollow metal hat block forming a part of my invention.

45 Figure 5 is an inverted plan or bottom view of the hat block.

50 Figure 6 is a front elevation of the im-

proved presser foot forming a part of my invention.

Figure 7 is a plan view of the presser foot shown in Figure 6.

55 Figure 8 is one of the spacing disks for varying the effective depth of the hat block.

A cross beam is shown at 8 and is supported from vertical standards 9, of which two pairs are used. These vertical standards are connected with supporting feet 10, serving as 60 pedestals.

A pair of horizontal beams 11, one of which is shown in Figure 2, and a pair of end pieces one of which is shown at 12, together 65 constitute a platform, supported by the vertical standards 9. These parts are held together by bolts 13.

A steam chamber 14 is mounted upon the platform just mentioned and connected with the steam chamber is a nozzle 15. To the 70 latter is connected a steam pipe 16, to which steam is admitted into the steam chamber.

Located within the bottom of the steam chamber is a baffle plate 17, shown more 75 particularly in Figure 2. This baffle plate is used for equalizing the distribution of the steam, as admitted into the steam chamber, and for this purpose is adjustable by means of bolts 18 and adjusting nuts 19 which support the weight of the baffle plate 80 17.

Another baffle plate is shown at 20, and is disposed in close proximity to an inlet opening 21.

85 An exhaust pipe 29, provided with a gate 30, operated by hand, communicates with the steam chamber through the inlet 21 as controlled by the gate 30. The exhaust pipe 29 leads to a blower, not shown, by aid of 90 which, a partial vacuum is formed within the steam chamber, as occasion may require.

The steam chamber 14 is provided at its top with a large annular flange 31, integral with it, and resting upon this flange is a 95 gasket 32 of annular form.

Engaging this gasket is a large annular flange 33, carried by a ring 34. This ring is integral with the flange 33, and extends 100 upwardly from the top of the steam cham-

ber, forming virtually a continuation thereof, as may be understood from Figure 2.

Bolts 31a, extending through the flanges 31 and 32 and through the gasket 32, hold these parts together.

Resting upon the annular flange 33 is a large cam ring 35, the form of which may be understood from Figures 2 and 3.

This cam ring is provided with a number 10 of cam faces 36 and is further provided with a handle 37 whereby it may be turned back and forth, as hereinafter more completely described.

A hat forming ring 38 of large size is located above the cam ring 35. A spider 39 is detachably mounted upon the hat forming ring 38.

The spider 39 carries a dowel pin 40 extending upwardly upon it, and is provided with a nipple 40a. The purpose of the nipple is to allow the passage of steam upwardly from the steam chamber 14.

Resting upon the spider 39 are spacing disks 42, 43, and resting upon these spacing disks is the hat block, shown at 44.

The form of the hat block may be understood from Figure 4. It is hollow and is provided with a bottom wall 45 of annular form, serving as a base, and with openings 30 46 and 47, and with perforations 48.

The opening 46 is for fitting over the nipple 40a, and the opening 47 is to fit over the dowel pin 40. Thus the spacing blocks 42, 43 and the hat block 44 are held together in group formation by means of the nipple 40a and dowel pin 40.

Each spacing block 42, 43, has the form shown in Figure 8, and is provided with a dowel hole 48a for registering with the dowel 40 hole 47 of the hat block.

A hat crown 49 and a hat brim 50 together constitute a hat body.

A forming ring, for the purpose of shaping the hat body, and particularly for demarking the brim from the crown, is shown at 51.

The forming ring 51 is detachably mounted upon and carried by a ring carrier 52, of the form shown more particularly in Figures 6 and 7. This ring carrier is hollow, but being made of metal and of rather massive construction it is quite heavy.

The forming ring 51 is provided with a pair of bolts 52a, by aid whereof it is detachably connected with the ring carrier 52, as may be understood from Figures 6 and 7.

The ring carrier 52 is provided with a pair of ears 53, 53, integral with it and extending radially inward.

For the purpose of raising and lowering the ring carrier 52 I provide a pair of guide rods 55, 55, extending vertically and provided with threaded portions 54, 54.

Engaging these threaded portions and ex-

tending across from one of the guide bars to the other is a lifting plate 56.

For the purpose of securing the lifting plate 56 to the threaded portions 54, 54, I use adjusting nuts 57, 57, 58, 58.

The lower ends of the guide rods 55 are provided with threaded necks 59, 59. These are simply threaded portions of reduced diameter as compared with the threaded portions 54, 54, and are integral therewith.

Fitted upon the threaded necks 59, 59 are nuts 60, 60, which extend through holes 61, 61 in the ears 53, 53, as may be understood from Figure 2. By this arrangement, the ring carrier 52 is mounted firmly upon the lower ends of the guide bars 55.

The guide bars 55, 55 extend through bearings 62, 62, supported by the cross beam 8, and are free to slide vertically in relation to these bearings.

For the purpose of raising and lowering the ring carrier 52 by means of the guide rods 55, 55, I provide a flexible supporting member 63, such as a chain, this being connected with a sector 64 as indicated more particularly in Figures 1 and 2.

The sector 64 is mounted firmly upon a shaft 65, and connected rigidly with the latter is a hand lever 66, whereby the sector may be rocked upon the axis of the shaft 65. This shaft is journaled upon a hanger 67, and carries a counterweight 68, for balancing the hand lever 66.

The guide rods 55, 55 carry stop collars 62a, 62a. These stop collars are adjustable relatively to the guide rods, and are adapted to rest upon the bearings 62, 62, so as to support the weight of the ring carrier 52 and parts carried thereby.

Whenever the guide rods 55, 55 are moved downwardly to their limit of travel, the stop collars 62a, 62a, carried by the guide rods, lodge upon the bearings 62, 62, so that the weight of the ring carrier 52 and forming ring 51 is now supported by the stop collars.

Thus when the ring carrier 52 and forming ring 51 occupy their lowermost positions, they are simply suspended from the stop collars, at a predetermined exact distance above the spider 39, this distance being determined by the adjustment of the stop collars 62a relatively to the guide rods 55, 55.

The operator, by grasping the hand lever 66 and operating it, can raise or lower the ring carrier 52, with the forming ring 51, so as to bring the forming ring down upon a hat brim, at a predetermined level above the spider 39, and thus at a definite distance below the top of the hat crown, as shown in Figure 2. Thus the forming ring demarks the hat crown from the brim, and assists in forming the hat.

A cam ring 35 is associated with a number of rollers 71, which respectively engage the cam faces 36, so that the operator, by grasp-

115

120

125

130

ing the handle 37 and turning the cam ring in a clockwise direction according to Figure 3, causes the several rollers 71 to be forced radially outward.

5 The hat forming ring 38 is provided with a number of slideways 69, extending radially outward, as may be understood from Figure 3.

10 There are eight of these slideways, arranged in the proximate form of a circle; only three of them, however, being shown in Figure 1.

15 Mounted within the respective slideways 69 are slides 70, adapted to be moved radially inward and outward relatively to a common center.

20 Each slide 70 carries a cam roller 71. The cam rollers 71 extend downwardly, into engagement with the faces 36 of the cam ring 35.

25 The operator, by grasping the handle 37 and rocking the cam ring back and forth, causes the slides 70 to move radially inward and outward. That is, the slides move outward as the cam rollers 71 are forced outwardly by the cam faces 36, and move inwardly by the tension of the springs 75.

30 Each slide 70 carries a gripping lever 72, mounted thereon by means of a bearing 73.

35 Each gripping lever 72 carries a jaw 74, facing downwardly as indicated in Figure 2.

40 Each slide carries a pair of tensile springs 75, and these springs are connected with the bearings 73, so that the tensile springs tend to move the slides radially inward.

45 Each slide 70 is provided with a jaw 76, facing upwardly and mating one of the jaws 74.

50 For the purpose of actuating the gripping levers 72 I connect these levers with pull rods 77. The pull rods extend downwardly, and at their lower ends are connected with a spider 78, the latter being connected with a treadle 79, as shown more particularly in Figure 1. The treadle is journaled upon a cross rod 81.

55 Another cross rod 82 serves as a limiting stop for preventing excessive upward travel of the treadle.

60 The spring 80 serves to retract the treadle 79, and by so doing to move the pull rods 77 upwardly, thereby causing the gripping levers 72 to rock, so that each jaw 74 is moved downwardly toward some one of the jaws 76.

65 The operator, by releasing the treadle 79 with his foot, so that the jaws 74 move downwardly toward their mating jaws 76, thus causes the jaws 74 and 76 to grip the adjacent edge of the hat brim 50, if such hat brim

70 is in the position indicated for it in Figure 2. If, next, the operator grasps the handle 37 and rocks the cam ring 35 so as to force the cam rollers 71 radially outward, the brim 50 of the hat body is stretched.

75 I will now describe the several suc-

sive steps which take place during the treatment of a hat body.

Assuming the machine to be in the condition indicated in Figures 1 and 2, the operator first raises the hand lever 66 to the upper limit of its travel so that the ring carrier 52 and the forming ring 51 are lifted clear of the hat block 44 and out of the way.

At practically the same instant, the operator depresses the treadle 79 and thereby 75 rocks the gripping levers 72, so that the jaws 74 are raised, and the hat brim is released. The operator now removes the hat body, and this leaves the machine clear.

The operator still keeping the treadle 80 down, next fits a new hat body in position, so that the crown covers the hat block and the brim extends loosely between the gripping jaws 74 and 76.

85 Next the operator lowers the hand lever 66 and brings the ring carrier 52 and forming ring 51 down, so that their weight is now supported mainly by the stop collars 62a, 62a, the forming ring thus fitting rather snugly 90 around the base of the crown, and serving to demarcate definitely the crown and brim.

95 Next the operator allows the treadle 79 to rise, which it readily does under tension of the spring 80, and this causes the gripping jaws 74 and 76 to grip the edge of the brim.

Then the operator grasps the handle 37 and rocks the cam ring 35, causing the cam rollers 71 to carry the slides 70 radially outward stretching the hat brim tightly.

100 Next the operator admits steam from the steam pipe 16 and nozzle 15 into the steam chamber 14. Steam from the steam chamber passes upwardly through the nipple 40a into the hollow hat block 44, and thence through the perforations 48 and through the substance of the hat crown.

105 The action of the steam upon the hat crown is to soften the material and render it somewhat plastic, so that under the stretching action to which it is being subjected it is made to fit neatly upon the hat block, its form for this purpose being rendered both definite and accurate.

110 The hat body being thus properly steamed and formed, the operator cuts off the supply of steam, and subjects the steam chamber 14 to the action of the suction blower, not shown, to which the pipe 29 leads.

115 This is conveniently done by simply opening the gate 30. This removes the steam from the steam chamber, and dries the hat body.

120 The operation is then repeated, as often as there are hat bodies to be treated.

125 The hat forming rings 51, being interchangeable, are of different sizes, for the purpose of accommodating the machine to hat bodies having hat crowns of different sizes.

130 In order to change the depth of the hat crown, the spacing disks 42 are changed or

interchanged as occasion may require, and as above described.

I do not limit myself to the precise mechanism shown, as variations may be made therein, without departing from my invention, the scope of which is commensurate with my claim.

Having thus described my invention, what I claim as new and desire to secure by Letters 10 Patent is as follows:

In a machine for treating hat bodies, the combination including means forming a steam chamber having a top wall with an opening therethrough, a hollow perforated 15 hat block supported upon said top wall having its interior communicating with said steam chamber through the mentioned opening, means for admitting steam into said steam chamber and into the interior of said 20 hat block and for exhausting the steam from said steam chamber and hat block, a forming ring arranged above the steam chamber and movable into and out of position encircling the hat block adapted for holding a hat body 25 closely about the exterior surface of the hat block and demarking the crown and brim of the hat body and leaving the brim of the hat body extending radially across the top wall of the steam chest away from said hat block, 30 a plurality of gripping members slidably mounted upon said top wall to slide radially thereof toward and away from the hat block adapted for gripping the brim portion of the hat body and stretching the same radially 35 across the top wall of the steam chest away from the hat block, and operating means for said forming ring and said gripping members.

Signed at New York city, in the county of 40 New York and State of New York, this 14th day of April, 1930.

GEORGE W. CUMING.
